ATOMIZER HEAD

Harry M. Marsh, Hamilton, Ontario, Canada, assignor to The Bahnson Company, Winston-Salem, N. C., a corporation of North Carolina

Application April 14, 1938, Serial No. 202,115
In Canada October 6, 1937

10 Claims. (Cl. 299—59)

This invention relates to atomizer heads and particularly to atomizer heads of the type in which a liquid is sprayed or atomized by high pressure gas or air.

5 An object of this invention is to provide an atomizer head of simple and economical construction which includes mechanism for automatically cleaning both the liquid and the gas nozzle upon a predetermined reduction in the
10 gas pressure. An object is to provide an atomizer head having concentric liquid and gas nozzles that are axially slidably relative to each other and to a stationary cleaning rod; the nozzles in operative position providing a central liquid
15 outlet surrounded by an annular gas outlet, and the nozzles being movable into inoperative positions with the inner nozzle telescoped upon the cleaning rod and projected through the outer nozzle. A further object is to provide an atomizer head of the type stated in which the nozzles are projected into operative positions by the pressure of the gas or air, and are returned to inoperative positions by a spring system.

These and other objects and advantages of
25 the invention will be apparent from the following specification when taken with the accompanying drawing in which:

Fig. 1 is a longitudinal central section through an embodiment of the invention, the parts being
30 shown in operative or spraying position;

Figs. 2 and 3 are end elevations of the outlet end and the liquid end, respectively, of the same;

Fig. 4 is a longitudinal sectional view, similar to Fig. 1, but showing the parts in inoperative
35 or cleaning position;

Figs. 5 and 6 are end elevations of the inner and outer ends, respectively, of the nozzle assembly; and

Fig. 7 is a perspective view of the liquid nozzle.
40 In the drawing, like numerals of reference indicate corresponding parts in the different figures.

The particular embodiment shown in the drawing was designed for use in a humidifier system
45 of the type in which the flow of high pressure air through a small outlet creates a suction for lifting water from a level somewhat below that of the air outlet.

In the drawing, the reference numeral 1 indicates a cylindrical casing section having a threaded air inlet opening 2, and a threaded water inlet connection 3. For convenience of description, reference will be made to the relative location of the parts when the cylindrical casing
55 is vertically arranged as shown in Figures 1

and 4, but it is understood that the axis of the atomizer head may be at any desired inclination when the device is in use. The interior of the cylindrical casing section 1 is counterbored to provide a minimum diameter bore section 4 forming a water inlet chamber adjacent its lower end and an upper bore section 5 of larger diameter forming an air inlet chamber, the lower bore section having a lateral vent opening 6 and the upper communicating with the air inlet 2. 10

The lower portion of a nozzle sleeve 7 is ground to form a piston for a sliding fit within the bore section 4. The upper portion of the sleeve 7 is tapered to form a water nozzle 8, the nozzle sleeve 7 having a bored hole 9 through the center for a waterway. Squared guides 10 on the upper portion of the nozzle sleeve 7 are spaced apart by a squared guide section 11 of lesser size, the squared sections thus providing four longitudinal passages of sector shape, in cross-section, 20 for the flow of water along the nozzle sleeve. The air nozzle 12 is counterbored from the lower end and has an air outlet 13 at the top end. A cup leather washer 14 forming a piston is secured to the lower end of the sleeve of the air nozzle 12 by a nut 14' threaded upon the threaded portion of the air nozzle. The washer 15 below the cup leather has a depending flange which retains the series of stop pins 16 in radial openings in the nozzle sleeve 12, the inner ends of 30 the pins being loosely seated against the liquid nozzle 7 at the smaller size squared section 11. Relative axial movement of the nozzles is thus limited by play of the stop pins between the squared sections 10. Within the upper end of 35 the casing 1 is fastened a sleeve 17 for holding the spring 18 in position, the lower end of this sleeve acting as a stop contacted by the nut 14' when the nozzles are in the operating position
40 as shown in Fig. 1.

A rod or wire 19 for cleaning the water nozzle 8 is fixed to the stem 20 which has its lower end bent over at right angles to seat in the counterbored recess 21 in the water inlet nozzle 3. 45

It is customary to use air at about 30 pounds pressure for atomizing the water, and the strength of the spring 18 which engages the sleeve 17 and the air nozzle may be so related to the area of the nozzle sleeve 12 that the nozzle sleeve moves inwardly when the air pressure falls below 10 pounds per square inch. This closes the air outlet by causing the tapered nozzle 8 to plug the air outlet and shut off the suction on the water supply and prevents the dis- 50 55

charge of water in large drops when the air pressure falls below a value effective to project the water as a fine mist which will evaporate in the surrounding air.

5 As shown in Fig. 4, the dimensions of the parts are such that the cleaning rod 19 extends completely through the water nozzle tip 8 when the nozzle is in its inward position as shown in Fig. 4. When the air pressure within the casing section 10 1 is increased above the predetermined value, the piston sleeve of the air nozzle 12 moves outwardly to carry the air outlet away from the water nozzle 8 sufficiently to form an annular air passage, thus permitting a discharge of high pressure air through the said passage to suck water through the nozzle 8 and atomize it. This movement of the piston sleeve 12 also pushes outwardly the piston sleeve 7 by the stop pins 16 engaging the upper squared guide 10, bringing the water 20 nozzle 8 into exact atomizing position in relation to the air outlet 13, at the same time moving the water nozzle tip 8 away from the cleaning rod or wire 19 allowing a free passage of water to the water nozzle 8.

25 It is to be noted that the spring 18 is located outside of both the air and water spaces and that the opening 6 vents any leakage of pressure air past the sliding fit of the piston end of the sleeve 7 of the water nozzle to the atmosphere.

30 A groove 22 in the piston sleeve 7 will act as a seal to further prevent leakage of air through the vent opening 6. The sliding fit of the lower piston end of the sleeve 7 seals the bore section 4 against atmospheric pressure through the vent opening 6, so as not to interfere with the suction lift of the water created by air passing through the opening 13 at the tip 8 of the water nozzle.

It will be apparent that the invention is not limited to the specific construction herein described and illustrated and that various changes may be made in the shapes, sizes, and relative locations of the parts, without departure from the spirit of my invention as set forth in the following claims.

45 I claim:

1. In an atomizer head, the combination of a casing having inlets for two fluids, a nozzle sleeve longitudinally slidable in the casing and having a fluid outlet opening at its outer end; a second nozzle sleeve longitudinally slidable in the first-mentioned sleeve, the second nozzle sleeve being adapted to enter the opening of the first-mentioned nozzle sleeve to define an annular outlet, and a stationary cleaning rod secured to the casing and extending longitudinally within the second-mentioned nozzle sleeve, the two sleeves being movable relative to one another and to the cleaning rod from an operative position to a position in which the cleaning rod clears the inner nozzle and the inner nozzle projects through and clears the outer.

2. An atomizer head according to claim 1, wherein the inner end of the first nozzle sleeve carries a piston fitting in the casing above one fluid inlet, whereby fluid pressure may be exerted against the piston to move the sleeve to operative position, and a spring engages the casing and the said first nozzle sleeve to bias that nozzle sleeve to the cleaning position, stop means being also provided limiting the extension movement of the outer sleeve relative to the casing and the movement of the outer sleeve relative to the inner in either direction.

3. An atomizer head as claimed in claim 1, 75 wherein one fluid inlet enters the casing below the

first nozzle sleeve, and the second fluid inlet enters the casing below and axially of the second nozzle sleeve, said second nozzle sleeve having its inner end formed as a piston closely fitting said second fluid inlet.

4. In an atomizer head, the combination of a casing counterbored to form two fluid inlet chambers of different diameters and in axial alignment, a fluid nozzle having a conical discharge end and having its inner end formed as a piston closely fitting the chamber of smaller diameter which communicates with the bore of the nozzle, a second nozzle sleeved on the first-mentioned nozzle and having its inner end formed as a piston closely fitting the chamber of larger diameter and its outer end formed with an aperture which the coned end of the first-mentioned nozzle may enter to define an annular outlet or to clear the same, a restricted passage leading from said chamber of larger diameter through the outer nozzle and communicating with the annular outlet, stop means limiting the outward movement of the outer nozzle under the influence of fluid pressure in the chamber of larger diameter, a spring engaging the casing and the outer nozzle and tending to retract the outer nozzle to cause the coned end of the inner nozzle to project through and clean the annular outlet, stop means limiting the inward movement of the inner nozzle relative to the outer, the coned nozzle end entering the aperture in the end of the outer nozzle serving to limit the inward movement of the outer nozzle relative to the inner nozzle, and a stationary cleaning rod connected to the casing and extending through the inner nozzle to a point such that, when the said nozzle is retracted, the end of the cleaning rod extends into and cleans the outlet thereof.

5. An atomizer head according to claim 4 in which the stop means limiting the inward movement of the inner nozzle relative to the outer comprises stop pins extending inwardly from the outer nozzle to engage a reduced diameter portion of the inner nozzle.

6. An atomizer head according to claim 4 in which a vent opening is formed in the casing leading from the inlet chamber of smaller diameter to the atmosphere, the piston end of the inner nozzle covering the inner end of the vent.

7. An atomizer head according to claim 4 in which the stationary cleaning rod has a radially extending inner end seated in a counterbored recess in the casing.

8. In an atomizer head, the combination of a casing counterbored to form two fluid inlet chambers of different diameters and in axial alignment; a fluid nozzle having a conical discharge end and having its inner end formed as a piston closely fitting the chamber of smaller diameter which communicates with the bore of the nozzle; a second nozzle sleeved on the first-mentioned nozzle and having its inner end formed as a piston closely fitting the chamber of larger diameter and its outer end formed with an aperture which the coned end of the first-mentioned nozzle may enter to define an annular outlet or to clear the same; a restricted passage leading from said chamber of larger diameter through the outer nozzle and communicating with the annular outlet; a sleeve forming part of the casing and extending within the outer end of the body of the casing in spaced relationship thereto, the outer nozzle sliding in said sleeve; a shoulder on said outer nozzle adapted to engage the inner end of the said sleeve to limit the outward movement

of the outer nozzle under the influence of fluid pressure in the chamber of larger diameter; a coil spring fitted over said guiding sleeve engaging the outer nozzle and tending to retract the outer nozzle and cause the coned end of the inner nozzle to project through and clear the annular outlet; stop means limiting the inward movement of the inner nozzle relative to the outer, the coned nozzle end entering the aperture in the end of the outer nozzle serving to limit the inward movement of the outer nozzle relative to the inner nozzle; and a stationary cleaning rod connected to the casing and extending through the inner nozzle to a point such that, when the said nozzle is retracted, the end of the cleaning rod extends into and clears the outlet thereof.

9. In an atomizer head, the combination of a casing; a stationary cleaning rod coaxial with the casing; concentric nozzles coaxial with the cleaning rod, said nozzles being slidable longitudinally relative to one another, the said nozzles in operative position providing a central fluid

outlet surrounded by an annular fluid outlet, said nozzles also being movable to project the cleaning rod through the central fluid outlet and the inner nozzle through the outer nozzle to eject any foreign matter from the annular fluid outlet. 5

10. In an atomizer head, the combination of a casing, a stationary cleaning rod coaxial with the casing; concentric nozzles coaxial with the cleaning rod, said nozzles being slidable longitudinally relative to one another, the said nozzles 10 in operative position providing a central fluid outlet surrounded by an annular fluid outlet, said nozzles also being movable to project the cleaning rod through the central fluid outlet and the inner nozzle through the outer nozzle to eject any 15 foreign matter from the annular fluid outlet, pneumatic means for moving the movable nozzles to the operative position, spring means for moving the movable nozzles to the cleaning position, and stops determining the two positions of 20 the said nozzles.

HARRY M. MARSH.
